WELDER'S HELMET AND SHIELD

Arthur C. Tompkins, 11802 E. 59th St.,

Kansas City 38, Mo.

Filed May 2, 1961, Ser. No. 107,118

1 Claim. (Cl. 2-8)

This invention relates to new and useful improvements in a welder's combination helmet and shield, and relates particularly to a combination device of the character described comprising a helmet or other head engaging device with a face and eye shield attached adjustably thereto for movement selectively to operative and inoperative positions, and intermediate positions.

An important object of the present invention is the provision of a device of the character described having means whereby the shield is positioned firmly and accurately in any one of a plurality of predetermined positions required in normal usage, but which is nevertheless releaseable for movement from one position to another by manual pressure exerted thereon.

Another object is the provision of a device of the character described wherein the pre-determined positions of the shield may be adjusted to the preference of the individual user.

Still another object is the provision of a device of the character described having novel latch means whereby the shield may be quickly and easily detached from and connected to the head-engaging portion. This provision is particularly useful when the head-engaging portion is a safety helmet or "hard hat," and safety regulations require said helmet to be worn whether the shield is in use or not.

Other objects are simplicity and economy of construction, efficiency and dependability of operation, and adaptability for use with face-protecting safety devices other than welder's helmets.

With these objects in view, as well as other objects which will appear in the course of the specification, reference will be had to the drawing, wherein:

FIG. 1 is a side elevational view of a welder's helmet and face shield embodying the present invention, showing the shield in its primary operative position in solid lines, and in other positions in dotted lines,

FIG. 2 is an enlarged, fragmentary sectional view taken on line II-II of FIG. 1, with parts left in elevation,

FIGS. 3 and 4 are enlarged, fragmentary sectional views taken respectively on lines III-III and IV-IV of FIG. 2, and

FIGS. 5 and 6 are fragmentary sectional views taken respectively on lines V-V and VI-VI of FIG. 4.

Like reference numerals apply to similar parts throughout the several views, and the numeral 2 applies generally to the helmet or head engaging portion of the device, while the numeral 4 applies generally to the face mask or shield. The helmet may be formed of steel or other rigid material to constitute the usual safety "hard hat." It customarily has disposed therein adjustable head bands for comfort and to adjust to the head size of the wearer, but these form no part of the present invention and are not here shown. If the mask is to be used in areas not requiring the use of a safety helmet, the head-engaging portion may comprise simply a head band device to serve as a mounting for the mask or shield. The mask or shield 4 is usually formed of fiber, plastic, sheet metal or other lightweight material, and comprises a cylindrically curved front portion 6 in which is mounted a window frame 8 usually containing darkly tinted safety glass, generally planar and parallel vertical side panels 10, and a generally spherically curved top panel 12 joining the upper edges of said front and side panels.

Side panels 10 of the shield extend rearwardly adjacent the respectively opposite sides of helmet 2, and each of

2

said side panels is pivotally connected to said helmet by means including a pivot shaft 14, the shafts at the opposite sides of the helmet being coaxially disposed on a horizontal axis transverse to said helmet. Each of said shafts extends rotatably through the associated side panel 10 of the shield. Externally of said side panel, said shaft extends through a countersunk washer 16 and a helical compression spring 18, and has a nut 20 threaded on its outer end. Spring 18 is compressed between said washer and said nut. Internally of side panel 2, shaft 14 passes successively through a circular clutch plate 22 which rests against the inner surface of side panel 10, and a second circular clutch plate 24 which overlies the inner surface of plate 22 and is coextensive therewith. Shaft 14 is freely rotatable in and longitudinally movable with respect to plate 22, but is welded or otherwise rigidly affixed to plate 24. Clutch plate 22 is provided with an integral, radially extending arm 26 lying against the inner surface of side panel 10, said arm having a cross-bar 28 at its outer end in which is formed an arcuate slot 30 concentric with the axis of clutch plate 22. A bolt 32 extends through side panel 10 and slot 30, and has a nut 34 threaded on the inner end thereof, so that when said bolt is tightened to clamp cross bar 28 against side panel 10, clutch plate 22 is secured against rotation relative to the shield. Clutch plate 22 has a plurality of radial ribs or offsets 36 formed thereon, said ribs being regularly spaced angularly of the plate, and clutch plate 24 has a matching set of grooves 38 formed therein and engaging ribs 36, being held yieldably in engagement therewith by spring 18. Said ribs and grooves are of rounded cross-sectional contour, as best shown in FIG. 5, in order that the two clutch plates may be rotated relative to each other by applying sufficient rotational torque thereto to cause said ribs and grooves to cam said clutch plates relatively apart against the pressure of spring 18.

Affixed to each of shafts 14 in inwardly spaced relation from the associated clutch plate 24 is a short, rod-like stud 40. Said studs are disposed at right angles to shafts 14 and parallel to each other, extending generally horizontally and rearwardly with respect to helmet 2. Each stud is inserted rearwardly and slidably through the tubular barrel portion 42 of a latch body member 44 which is in turn affixed to the adjacent side of helmet 2 as by rivets 46. Said stud extends outwardly from the rearward end of barrel 42, and has a notch 48 formed in the upper side of the extended portion thereof. Said notch is engaged by a pawl 50 pivoted in latch body 44 at 52, whereby to lock stud 40 against withdrawal from barrel 42. The pawl is provided with an operating lever 54 whereby said pawl may be manually disengaged from notch 48, and with a spring 56 whereby it is resiliently biased toward its engaging position.

In use, the user may detach the mask or shield from the helmet by pressing the two operating levers 54 forwardly to release pawls 50 from stud notches 48, whereupon the shield may be moved forwardly to withdraw studs 40 from latch barrels 42. The mask may be reattached simply by inserting studs 40 in barrels 42, and pressing them rearwardly until they are engaged by pawls 50. The shield would ordinarily be removed in this manner only when the user plans to work for a considerable period of time without the mask, but where good safety practice requires the continued use of the safety helmet 2. In common usage, a welder merely grasps the shield and pushes it up or down to the desired position, torque on the mask causing ribs 36 of clutch plates 22 to act as cams forcing clutch plates 24 inwardly against the pressure of springs 18 until the grooves of plates 24 are freed from the ribs of plates 22 to allow the shield to pivot. Side panels 10 of the shield are sufficiently

yieldable to spread to the degree required for this movement. The shield will be secured releaseably in the next position when the ribs of plates 22 are brought into registry with and are engaged by the next set of grooves of plates 24. Thus while the shield may be moved freely from one position to another as desired, it is nevertheless indexed accurately in any of a series of predetermined positions, and restrained against accidental movement. This is a distinct advantage over previous structures within my knowledge wherein the shield is held in any position simply by frictionally loaded pivots. In such structures, the pivots repeatedly work loose so as to allow uncontrolled movement of the shield, and there is nothing to provide that the shield will be indexed accurately in predetermined positions.

In general practice, welders desire these alternative positions of the shield 4, first the normal position of use shown in solid lines in FIG. 1, second a completely inoperative position allowing unrestricted vision as shown in dotted lines at 4' in FIG. 1, and third an intermediate position as shown in dotted lines at 4" in FIG. 1, in which the wearer is permitted free vision of his own normal field of work, but in which his eyes are protected from the rays of the welding flame or arc of other welders who may be working nearby. The present structure provides these three positions. However, it will be readily apparent that a greater or smaller number of positions could be provided, as desired, simply by changing the angular spacing between the ribs and grooves of clutch plates 22 and 24.

It is also desirable that the various positions of the shield, particularly the solid line position shown in FIG. 1, be adjustable to suit the individual requirements and preferences of each individual user. Factors influencing the proper positioning of the shield are the habitual working position of the user, whether he must wear spectacles or not, whether the particular welding job is disposed high or low with respect to the operator's position, and others. In the present structure this adjustment may be accomplished by loosening bolts 32, moving the shield to the precise position desired without disengaging the clutch plates, and then tightening said bolts.

While I have shown and described a specific embodiment of my invention, it will be readily apparent that many minor changes of structure and operation could

be made without departing from the spirit of the invention as defined by the scope of the appended claim.

What I claim as new and desire to protect by Letters Patent is:

- 5 In combination, a head-engaging member adapted to be worn in the manner of a hat, a face shield adapted to be positioned forwardly of the face of the wearer when said head-engaging member is so worn, and including a pair of side panels extending rearwardly adjacent respectively opposite sides of said head-engaging member, and connecting means joining each of said side panels to said head-engaging member whereby said shield may be pivoted relative to said head-engaging member on a horizontal transverse axis, said connecting means including 10 a shaft extending through a side panel of said shield for rotation and longitudinal movement, resilient means urging said shaft outwardly with respect to said side panel, a first clutch plate disposed against the inner face of said side panel and having a series of regularly spaced radial ribs on the inner face thereof, said shaft extending centrally through said clutch plate and being rotatable and longitudinally movable therein, means fixing said 15 first clutch plate to said side panel, a second clutch plate affixed on said shaft inwardly from said first clutch plate and having a series of grooves formed in the outer face thereof matching with the ribs of said first clutch plate, and being urged against said first clutch plate by said resilient means whereby said grooves engage said ribs, said ribs and grooves being of rounded cross-sectional counter 20 whereby said clutch plates may be rotated relatively by the application of considerable torque to one of said clutch plates, a rod-like stud affixed to the inner end of said shaft and extending at right angles thereto, a latch body affixed to said head-engaging member and having a tubular barrel receiving said stud slidably therein, and 25 a spring-loaded pawl carried movably by said latch body and engaging a notch formed therefor in said stud to prevent withdrawal of said stud from said barrel.
